UNITED STATES PATENT OFFICE.

GEORGE AMBORN, OF CHAPINVILLE, CONNECTICUT, ASSIGNOR TO J. H. WILLIAMS & CO., OF BROOKLYN, NEW YORK, A CORPORATION OF NEW YORK.

TOOL-HOLDER.

1,120,782.

Specification of Letters Patent. Patented Dec. 15, 1914.

Application filed February 8, 1912. Serial No. 676,413.

To all whom it may concern:

Be it known that I, GEORGE AMBORN, a citizen of the United States, residing in Chapinville, in the county of Litchfield and State of Connecticut, have invented certain new and useful Improvements in Tool-Holders, of which the following is a specification.

This invention relates to tool holders and aims to provide certain improvements therein.

The invention is particularly directed to tool holders for lathes or other machines which are adapted to hold a cutting off or side tool, the principal object being to provide means for clamping a tool or cutter rigidly upon the holder in such manner that it will not work loose in use.

In the preferred form of the invention the tool holder is provided with a shallow groove on one side, the edges of which are undercut and the tool is provided with beveled edges adapted to fit in the groove in the holder. Means are provided for clamping the tool so as to prevent longitudinal displacement, which means are inclined to the vertical axis of the tool, preferably to such an extent that the clamping means extend at right angles to the upper beveled edge of the tool. Such clamping means are best constructed as a plate extending over the upper edge of the tool near its cutting end, the plate being pressed down by a set screw or other suitable device, and having on its edge opposite the tool a lip or the like for engaging the tool holder whereby to prevent the plate from slipping.

In the drawings wherein I have illustrated one form of the invention,—Figure 1 is a side elevation of the holder and tool. Fig. 2 is a top or plan view of Fig. 1. Fig. 3 is a cross section taken on the line 3—3 in Fig. 1.

Referring to the drawings, let A indicate the holder body which is formed along one side with an open groove B having undercut edges C and D. In the construction shown the edge C is continued the entire length of the tool while the edge D is interrupted at the point E, so as to permit the application to the tool of a clamping plate F. Preferably the tool holder is provided near its front end with an enlargement G which is shown as provided with a screw-

threaded bore H designed to receive a set screw I for the plate F, as best seen in Fig. 3.

The tool J is formed with upper and lower beveled edges designed to fit the undercut edges of the groove B so that the tool is capable of sliding within the groove, but is held against lateral displacement therein.

The clamping plate F is preferably generally flat in form and extends at a slightly obtuse angle to the tool or cutter J, as best seen in Fig. 3. Its general direction is, however, parallel to the transverse direction of the upper beveled edge of the tool. The set screw I or its equivalent which presses the clamping plate F down upon the tool is also given a suitable inclination to the vertical axis of the tool, so that it is perpendicular to the plate F. For this purpose the threaded bore H in the enlargement G is inclined with relation to the vertical as shown. Preferably also the upper face of the enlargement G is given an inclination which corresponds to that of the lower face of the plate. I also prefer to form a lip or flange L on the side of the clamping plate which is opposite to the tool, such lip fitting over the side of the enlargement and preventing any slipping or turning movement of the plate. The clamping plate bears or fulcrums on the top of the enlargement G near one side, the enlargement being preferably formed with a rib or fulcrum R for this purpose. The plate is best made with a tapered recess M on its upper side, surrounding the bolt I, and the latter is provided with a corresponding bevel which fits the recess.

By the present invention I provide a tool holder in which the tool is firmly and rigidly clamped in position so that there is little or no liability of the tool being displaced in use. The clamping plate because of its inclination to the tool presses the latter firmly against the bottom face of the groove and holds the tool more effectively against any side or end strains than when the clamp extends at right angles to the vertical axis of the tool.

While I have shown and described one form of the invention, it will be understood that I do not wish to be limited thereto, since various changes may be made therein

without departing from the invention which will be within the scope of the appended claims.

What I claim is:—

- 5 1. A tool holder having a tool recess therein with a bottom and a side wall, a clamping plate, a fulcrum on said tool body, said clamping plate being adapted to bear on said fulcrum and on a tool in said recess, means for applying a clamping force to said clamping plate, said clamping plate having a face thereon adapted to transmit to said tool direct components of the clamping force in directions to press the tool against the bottom and side walls of the tool recess, said clamping force acting in the direction of pressure of said clamping plate.
- 10 2. A tool holder having a tool recess therein with a bottom and a side wall, and a clamping plate for engaging a beveled edge of the tool, said clamping plate having a flat underside substantially parallel with said bevel edge adapted to fulcrum on said tool holder and to bear upon the bevel edge of said tool, and means for pressing said clamping plate against the tool with direct force-components for pressing said tool against both said bottom and side walls, said means acting substantially parallel to the direction of pressure of said clamping plate.
- 15 3. A tool holder having a tool recess therein with a bottom and a side wall, a

clamping plate adapted to fulcrum on the tool holder and to press upon a bevel edge of a tool in said recess, and a screw device engaging said clamping plate, said clamping plate having a face thereon adapted to transmit to said tool direct components of the force exerted by said screw in directions to press said tool against the bottom and side walls of said recess, said screw acting in the direction of pressure of said clamping plate.

4. A tool holder having a tool recess therein with a bottom and a side wall, a clamping plate, a fulcrum on said tool body, said clamping plate being adapted to bear on said fulcrum and on a tool in said recess, a screw threaded bolt, having means thereon for turning it, for applying a clamping face to said clamping plate, said clamping plate having a face thereon adapted to transmit to said tool direct components of the clamping force in directions to press the tool against the bottom and side walls of the tool recess, said clamping force acting in the direction of pressure of said clamping plate.

In witness whereof, I have hereunto signed my name in the presence of two subscribing witnesses.

GEORGE AMBORN.
